UNITED STATES PATENT OFFICE

134,618

DESIGN FOR A SOFA

Mendell M. Selig, Leominster, Mass.

Application October 10, 1940, Serial No. 95,753

Term of patent 7 years

To all whom it may concern:

Be it known that I, Mendell M. Selig, a citizen of the United States residing at Leominster, in the county of Worcester and State of Massachusetts, have invented a new, original, and ornamental Design for a Sofa, of which the following is a specification, reference being had to the accompanying drawings, forming part thereof.

Fig. 1 is a perspective view;
Fig. 2 is a rear elevational view; and
Fig. 3 is an end elevational view of a sofa showing my new design.

I claim:
The ornamental design for a sofa, as shown.

MENDELL M. SELIG.
